United States Patent Office.

JAMES A. CLARKE, OF NEW YORK, N. Y.

Letters Patent No. 75,526, dated March 17, 1868.

IMPROVED FERRY-BRIDGE GUARD.

The Schedule referred to in these Letters Patent and making part of the same.

Be it known that I, JAMES A. CLARKE, of the city, county, and State of New York, have invented a new and useful Self-Acting Ferry-Bridge Guard for preventing accidents in passing to and from ferry-boats; and I do hereby declare and ascertain my said improvements, referring to the accompanying drawing, making a part thereof, in which—

Figure 1 is a plan.

Figure 2 is a sectional elevation.

The great danger from the carelessness of passengers, and from accidental causes, in hurrying on and off ferry-boats has long rendered some safety-guard necessary, but the difficulty of applying any efficient remedy that would not be too complex or difficult in putting into operation has, so far, retarded the introduction of anything heretofore for that purpose.

My invention is made to remedy any defect heretofore existing, and furnishes a simple, efficient, and cheap guard, that is at all times self-acting and perfectly adjustable.

The construction is as follows: The floating or other bridge is like those now in general use in all essential particulars, as at *a*, in the drawing. The windlasses on each side should be entirely fenced off from and outside of the footways, as at *b*. The fender at the front edge of the bridge, instead of being a permanent part of the bridge, is independent thereof, as at *c*, and is supported on two slide-pieces, *d*, that run horizontally back under the bridge. This fender is suspended at its front by two suspension-rods or chains, *e*, and at the rear end there is an arm, *f*, jointed to each of the two slide-pieces, *d*, which supports it, and allows the fender *c* an easy movement out and in. In rear of the fender there is an axis running across the outer edge of the bridge at *g*, having a pulley or wheel, *h*, at each division-frame of the bridge, between the roadway and footway. These pulleys are connected, by a cord, *i*, with the slide *d* on each side, as clearly seen in the drawing, so that as the slides *d* move out and in, said pulleys and axis revolve about a quarter revolution. To axis *g* there is firmly and securely hinged a draw or guard-plank, *k*, properly braced, so as to rise and fall at its outer end as the axis turns. There is a little play to this piece on the axis to accommodate it to the varying differences of level between the boat and bridge. A counterbalance-weight, *l*, holds the guard up.

The apparatus thus constructed is put into operation as follows: When a ferry-boat is coming into the slip, the guard *k* is standing up, like a gate, at the lower end of the bridge, and prevents the rush of passengers to or from the boat, until it comes up close and strikes the fender *c*, driving it in, and lowering the guard or draw upon the boat. The boat is in the mean time hooked by the mooring-chains at the sides in the usual way. On leaving the slip, as soon as the boat recedes from the fender, it slides forward, and the draw is raised, a barrier against the passage of any one who would attempt to pass to or from the boat, thus presenting a self-acting barrier, only removed when the boat is safely in its place in the slip and moored.

Having thus described my new and useful ferry-bridge guard, what I claim as new, and for which I desire Letters Patent, is—

The self-acting draw *k*, actuated by the fender *c*, substantially as and for the purposes set forth.
